[57] CLAIM

The ornamental design for a mounting bracket, as shown and described.

DESCRIPTION

FIG. 1 is a perspective view of a mounting bracket showing my new design;

FIG. 2 is a front view;

FIG. 3 is a rear view;

FIG. 4 is a left side view;

FIG. 5 is a right side view;

FIG. 6 is a top view; and,

FIG. 7 is a perspective view of a second embodiment of the design of FIG. 1, the only difference being that the base member has a finish that contrasts to the rest of the mounting bracket.

The undisclosed elevational and plan views for the second embodiment are identical to the same views shown in the first embodiment.
